CLAIM

[21] Appl. No.: 406,382

The ornamental design for a sign support stand, substantially as shown and described.

DESCRIPTION

FIG. 1 is a top front perspective view of a sign support stand, showing my new design; and
FIG. 2 is an exploded perspective view thereof taken from behind and below.

The broken line disclosure of the cards in FIG. 1 is for illustrative purposes only and forms no part of the claimed design.
